UNITED STATES PATENT OFFICE.

JOHN M. MANGAN AND JAMES P. BURNS, OF MINERS MILLS, PENNSYLVANIA.

HOPPER-DOOR-OPERATING MECHANISM.

Application filed October 3, 1923. Serial No. 666,368.

To all whom it may concern:

Be it known that we, JOHN M. MANGAN and JAMES P. BURNS, citizens of the United States of America, and residents of Miners Mills, in the county of Luzerne and State of Pennsylvania, have invented certain new and useful Improvements in Hopper-Door-Operating Mechanism, of which the following is a specification.

10 This invention relates to railway rolling stock, and particularly to an improvement relating to door closures and holders for the doors of hopper cars.

It is an object of this invention to produce 15 novel means whereby door operating and holding means may be provided as substitutes for the holding means on cars now in common use that are held closed by ratchet wheels and pawls. The conventional types 20 of door operating and holding means for hopper cars develop lost motion to an extent that permits the doors to sag with respect to the door frame with which it coacts and the loss of contents of cars often results 25 especially where the shipment contains fine materials.

It is an object of this invention to produce novel means for closing the doors and holding them tightly closed to preclude the 30 losses referred to, while at the same time, each door may be expeditiously operated for moving it to an open or closed position, and for holding it against accidental opening.

It is a further object of this invention to 35 produce a door operating and retaining device that can be expeditiously substituted for the winding and holding means which include the ratchet wheel and dog now in common use; and furthermore, to provide 40 mechanism which will withstand unusual wear and strain after it has been installed.

It is furthermore an object of the invention to produce mechanism of the character indicated which will be comparatively inexpensive to manufacture and install in cars 45 now in common use, or which can be furnished as a part of the equipment of new rolling stock.

With the foregoing and other objects in 50 view, the invention consists in the details of construction, and in the arrangement and combination of parts to be hereinafter more fully set forth and claimed.

In describing the invention in detail, reference will be had to the accompanying drawings forming part of this application

wherein like characters denote corresponding parts in the several views, and in which—

Figure 1 illustrates a view in elevation of 60 a conventional type of car with a device embodying the invention applied thereto;

Figure 2 illustrates a detail view of the attachment for a car embodying the invention;

Figure 3 illustrates a detail view of the base plate of the device;

Figure 4 illustrates a sectional view on the line 4—4 of Fig. 2;

Figure 5 illustrates a sectional view on 70 the line 5—5 of Fig. 3; and

Figure 6 illustrates a perspective view of the worm bearing and its attaching means.

In these drawings 10 denotes a plate having apertures 11 to receive fastenings by 75 which the plate may be attached to a stationary part of a car, and preferably this plate is attached to a side frame of a car, and of course, it must be positioned in operative relation to the winding shaft 12 80 or the door operating shaft, which shaft, as stated, in the conventional construction is held in different positions of adjustment by a ratchet wheel and dog. The plate has an aperture 13 to receive the shaft, and the 85 face of the plate where it is apertured has a boss 14 beyond which the end of the shaft projects.

The plate is further provided with flanges 15 at each edge and the inner ends of the 90 said flanges are enlarged and recessed as at 16 to form bearings.

In the present embodiment of the invention, a worm 17 is employed and the worm has trunnions 18 at its ends, the said trunnions terminating in heads 19 that are angular in cross section in order that the said heads may be engaged by worm rotating means or implements such as a wrench, a crank, or the like.

As a means for rotatably supporting the trunnions of the worm in engagement with the bearings at the ends of the flanges, metal strips or plates 20 are secured against the face of the plate 10 and preferably in engagement with the flanges, and the said members 20 have open bearings 21 in which the trunnions 18 are fitted prior to the time the members 20 are adjusted and secured on the face plate, and the relation of parts 100 is such that the members 20 hold the trunnions in engagement with the bearings of 110

the flanges and prevent the trunnions from being disengaged from the positions in which they are placed. The members 20 have lateral extensions 22 to increase the bearing surfaces and these conform to and cooperate with the enlargements or extensions on the flanges of the plate so that the bearing for the trunnions of the worm will be of sufficient size as to withstand strain 10 incident to the use of the mechanism.

After the plate with the accompanying parts has been applied to the car frame with the door operating shaft projecting through the apertured plate and boss, a worm wheel 23 is secured on the door operating shaft in order that it engages the worm, and when the worm is rotated, it will result in opening or closing the door, according to the direction of rotation of the 20 worm. The pitch of the threads of the worm and the teeth of the worm wheel is such that the friction between the interengaging teeth and threads will serve to hold the door at different positions of adjustment 25 so that only by the application of power can the worm wheel be rotated.

The worm wheel may be secured on the shaft in any appropriate way, as by upsetting the end of the shaft, but the inventors 30 do not wish to be limited with respect to these details, as the main feature of the invention is the provision of means for positively actuating and positively holding the door operating shaft without employing the usual ratchet wheel and dog.

The worm wheel is preferably crowned in order to increase the engaging areas of the teeth with the worm, and it prevents the wheel from disengaging the worm.

40 We claim:

1. In a hopper door operating mechanism, a plate adapted to be attached to a hopper car in proximity to the door operating shaft thereof and having an aperture therein to

receive said shaft, flanges on the said plate 45 having bearings at their ends, a worm having trunnions, trunnion supporting elements engaging the trunnions for holding them in operative relation to the bearings of the flanges, the said trunnions having tool 50 engaging ends whereby the worm is rotated, and a worm wheel on the door operating shaft engaging the said worm.

2. In a device for converting hopper door holding means comprising a plate adapted 55 to be secured to a stationary part of a hopper car in operative relation to a door operating shaft thereof, a boss projecting from the face of the plate, the said plate and boss having an aperture, bearings formed on the 60 plate at the sides of the boss, a worm having trunnions, members having open bearings in which the trunnions are fitted, means for securing the members to the plate in positions to hold the trunnions of the worm in 65 engagement with the bearings of the plate, and a worm wheel adapted to be secured to the hopper door operating shaft meshing with the worm for operating and holding the said door.

3. In a device for converting hopper door holding means, a plate having flanges at its edges with bearings at their inner ends, a boss on the face of the said plate, the said plate and boss having an aperture for the 75 reception of a hopper door operating shaft, members having open bearings and adapted to contact the flanges whereby the openings of the bearings are guarded against the displacement of a journal, a worm having 80 trunnions at the end thereof, the said trunnions fitting in the bearings of the members, means for securing the members to the plate, and tool engaging heads on the ends of the trunnions.

JOHN M. MANGAN.
JAMES P. BURNS.
